ELECTRIC TREMULANT ATTACHMENT FOR
ACCORDIONS

Lester E. Rush, Great Falls, Mont.

Application August 9, 1937, Serial No. 158,250

6 Claims. (Cl. 84—376)

This invention relates to an electric tremulant attachment for accordions which will automatically cause the notes to sound with a tremulous tone.

5 It is an object of the invention to provide an attachment of the above-mentioned character which may be installed in the conventional accordion without material alterations and which embodies means for eliminating the tremulous 10 effect at the will of the operator.

A further object of the invention is to provide an attachment of the above-mentioned character which is simple and durable in construction, reliable and efficient in operation and inexpensive 15 to manufacture.

Other objects and advantages of the invention will be apparent during the course of the following description.

In the accompanying drawings, forming a part 20 of this specification and in which like numerals are employed to designate like parts throughout the same,

Fig. 1 is an end elevation of an accordion, partly in section, with the attachment installed 25 therein,

Fig. 2 is a perspective view of the accordion and attachment in separate relation,

Fig. 3 is a side elevation of the attachment, showing the motor mounted within the frame of 30 the attachment,

Fig. 4 is a side elevation of the opposite side of the attachment with the motor mounted outside the frame,

Fig. 5 is a section taken on line 5—5 of Fig. 4, 35 Fig. 6 is a detail perspective view of the switch mechanism for operating the free port valves,

Fig. 7 is a perspective view of the tremulant valve, and,

Fig. 8 is a fragmentary longitudinal section of 40 the tremulant valve.

In the drawings, wherein for the purpose of illustration I have shown a preferred embodiment of my invention, the numeral 5 denotes a conventional accordion in its entirety having the 45 usual bellows 6, with compartments 7 and 8 on opposite sides thereof containing the bass and treble reeds respectively.

Referring more particularly to my invention, the attachment consists of a partition 9 surrounded by a frame 10 adapted to be installed 50 between the bellows 6 and treble compartment 8 of the accordion. The partition 9 is composed of two separable boards and a bore 11 is formed between the partition boards to extend longitudinally of the partition adjacent its lower edge, the

bore being provided with opposed openings 12, at spaced intervals throughout its length, providing air passages through the partition. A tubular valve casing 13 is fixed within the bore 11 having a series of spaced openings 14 corresponding to 5 the openings 12 and adapted to register therewith. A rotary valve 15 of tubular construction is mounted to revolve within the casing 13 having opposed openings 16 at spaced intervals adapted to register with the openings 14 upon 10 rotation of the valve and disposed within the valve between the openings 16 are plugs 17 to prevent whistling and air leakage. The solid portion of the valve which passes the openings 14 is slightly narrower in width than the openings 15 15, so that at no time is the opening completely closed. The rotary valve extends beyond the ends of the casing 13 and is secured therein by means of a jam cap 18 affixed to the end of the valve by a set screw 19. The opposite end of the 20 rotary valve carries a gear wheel 20 which meshes with the worm 21 formed on the shaft 22 of the electric motor 23, the free end of the motor shaft being journaled in the bearing clamp 24. The motor 23 is mounted on the partition either 25 beyond the frame 10, as shown in Fig. 2, or may be mounted on the partition within the frame, as shown in Fig. 3. The motor is connected to a suitable source of electric current by the wires 25 and interposed in the circuit of the motor is a 30 rheostat 26 by means of which the speed of the motor is regulated.

A series of spaced free air ports 27 extend through the partition 9 adjacent its upper edge which are normally closed by valve plates 28 35 covered with a lining of soft leather 29. The valve plates are connected to arms 30 extending from the shaft 31 journaled in the bearing brackets 32 attached to the partition. A series of U-shaped loops 33 extend from the shaft 31 at 40 spaced intervals, the end loops being engaged by the leaf springs 34 affixed to the partition, which hold the valve plates in closed position. The intermediate loop is disposed in the path of movement of the cam face 35 of the disk wheel 45 36 mounted on one end of the shaft 37 which is journaled in the upper side member of the frame 10. A crank arm 38 is attached to the opposite end of the shaft 37 which is connected by means 50 of the rod 39 to the slide lever 40 slidably mounted in the outer face of the upper side member of the frame 10 and by moving the slide lever the wheel 36 is turned to bring the cam face 35 into engagement with the intermediate loop 33 on the 55

shaft 31, thereby rocking the shaft to swing the valve plates 28 to an open position.

In operation, the tremulant attachment is easily installed in the conventional accordion by separating the treble compartment from the bellows and inserting the frame 10. Upon starting the electric motor 23 the rotary valve 15 is revolved at a pre-determined speed causing a pulsating current of air to pass through the openings 12 when the bellows are actuated and thus cause the treble reeds to sound with a tremulous tone. When it is desired to eliminate the tremulant effect, the slide lever 40 is moved to turn the wheel 36 so as to rock the shaft 31 to open the valve plates 28 and allow a free flow of air through the ports 27 which changes the tone of the reeds from a tremolo to a plain tone without having to stop the motor. Thus, it is seen the tremulant effect may be brought into operation or eliminated at the will of the player.

It is to be understood that the form of my invention herein shown and described is to be taken as a preferred example of the same and that certain changes in the shape, size and arrangement of the parts may be made without departing from the spirit of the invention or the scope of the subjoined claims.

Having thus described my invention, I claim:

1. A tremulant attachment for accordions comprising a partition adapted to be inserted between the bellows and treble reeds of an accordion, said partition having a central longitudinal bore provided with opposed openings at spaced intervals, a rotary valve mounted to revolve in the bore of said partition having transverse passages therethrough at spaced intervals, said passages being of a size to permit communication between the opposite openings at all times and means for revolving said valve whereby the volume of air passing through said openings is varied.

2. A tremulant attachment for accordions comprising a partition adapted to be inserted between the bellows and treble reeds of an accordion, said partition having a series of spaced passages therethrough, a rotary valve intersecting the passages of said partition and having transverse passages therethrough, said passages being of a size to permit communication between the passages of said partition and valve at all times and means for rotating said valve to vary the volume of air passing through said passages.

3. A tremulant attachment for accordions comprising a partition adapted to be inserted between the bellows and treble reeds of an accordion, said partition having a series of spaced

passages therethrough, a rotary valve intersecting the passages of said partition and having transverse passages, said passages being of a size to permit communication between the passages of said partition and valve at all times, an electric motor mounted on said partition and gearing driven by said motor for driving said rotary valve to vary the volume of air passing through said passages.

4. A tremulant attachment for accordions comprising a partition adapted to be inserted between the bellows and treble reeds of an accordion, said partition having a series of spaced passages therethrough, a rotary valve intersecting the passages of said partition and having transverse passages therethrough, said passages being of a size to permit communication between the passages of said partition and valve at all times, means for revolving said valve to vary the volume of air passing through said passages, a series of free ports through said partition, valve plates normally closing said ports, and manual means for moving said valve plates to open said ports.

5. A tremulant attachment for accordions comprising a partition adapted to be inserted between the bellows and treble reeds of an accordion, said partition having a series of spaced passages therethrough, a rotary valve intersecting said passages of the partition and having transverse passages therethrough, said passages being of a size to permit communication between the passages of said partition and valve at all times, a gear wheel carried by one end of said rotary valve, a motor mounted on said partition, a worm carried by the shaft of said motor and meshing with said gear wheel, a series of free ports through said partition, valve plates normally closing said ports, a shaft connected with said valve plates for swinging the plates to open and close said ports and manually actuated means for rocking said shaft.

6. A tremulant attachment for accordions comprising a partition adapted to be inserted between the bellows and treble reeds of an accordion, said partition having a central longitudinal bore provided with opposed openings at spaced intervals, a rotary valve mounted to revolve in the bore of said partition having transverse passages therethrough, at spaced intervals, for register with the openings, said passages being relatively wider than said openings to permit direct communication between opposed openings at all times and mechanical means for rotating said valve at a predetermined constant speed.

LESTER E. RUSH.
